(57) **CLAIM**

I claim the ornamental design for a firewall bracket, as shown and described.

DESCRIPTION

FIG. 1 is a three-dimensional front perspective view of my new design for a firewall bracket with a moving rocker arm; FIG. 2 is another three-dimensional front perspective view thereof;

FIG. 3 is a front view thereof in an open configuration; FIG. 4 is a front view thereof in a closed configuration; FIG. 5 is a left side view thereof; FIG. 6 is a right side view thereof; FIG. 7 is a top view thereof; FIG. 8 is a bottom view thereof; FIG. 9 is a perspective view of a buffer element with the rest of the claim removed for clarity of disclosure; and, FIG. 10 is a front view of a buffer element with the rest of the claim removed for clarity of disclosure. The broken lines illustrate environmental structure and form no part of the claimed design.
